UNITED STATES PATENT OFFICE

LUIS HECTOR BARONE, OF BUENOS AIRES, ARGENTINA

FOOTWEAR

Application filed October 15, 1928. Serial No. 312,686.

The present invention has reference to a new type of shoe and has as its object the making of a shoe in which the welt is attached to the uppers and to the sole by means of nails or clips instead of by sewing, as is the usual method.

As will be explained hereinafter, the application of this idea to the manufacture of shoes carries many advantages and particularly so when applied to the manufacture of the type of shoe generally known as "sandals."

In order that this invention may be clearly understood and easily put into practical use, it has been illustrated by way of example in the accompanying drawings, in which:

Figure 1 is the side view of a shoe in accordance with the present invention.

Figure 2 is a cross-section of the said shoe taken through its toe.

Figures 3, 4 and 5 are broken cross-section views of the joint between the upper, sole, and welt of my shoe invention with the sections taken through the toe of the shoe.

In order to make matters as clear as possible, the nails are shown by dotted lines.

In the five views shown, equivalent or corresponding parts are indicated by the same numbers.

The welt 2 is fitted to the outer side of the shoe 1 and in the said welt 2, the nails 3 or clips are inserted, with their points pointing in the direction of the under side 35 of the sole and in such a manner that they hold together the welt 2, the uppers 4 and the sole 5.

The nail heads or clips may be left uncovered or may be hidden and various methods may be adopted in practice in order to obtain this object.

The nail heads may be hidden, for example, by employing a welt double the ordinary width, thus hiding the nails. In this case, 45 the welt would be applied with the flesh side of the leather uppermost, so that when the welt is turned back upon itself, the grain side of the leather will show.

The welt may also be split along its length 50 in order to obtain similar results as shown

in Figures 3, 4, and 5. According to the method shown in these figures the welt may be split along its length either on its outside edge or its inside edge or the split may be made at an angle to and lengthwise with the top of the welt, in each case forming a top flap *a* which may be folded down and cemented over the heads of the nails or clips in order to conceal them.

Another method by which the nail heads 60 or clips may be hidden is by the application of a second or covering welt on top of the one which is nailed, the said covering welt being stuck on or attached in any other suitable manner.

Similarly the nail heads or clips may be hidden by embedding them deeply in the welt and afterwards applying over these some of the various special preparations 70 which are manufactured for this class of work.

Some of the most important advantages of this new method of manufacturing shoes are set forth in the following instances:

Considerably fewer nails, or clips are required in this new method for attaching the uppers to the soles, thus economizing both material and machinery; furthermore, as this operation is of a very simple nature, it is unnecessary to employ expert labour, 80 thus considerable economy in wages is effected.

Another advantage of this new method lies in the fact that it is unnecessary to keep the last in the shoe during the whole course 85 of its manufacture as is the case with the usual system, considerable economy in lasts and in storage space thus being effected.

Another important advantage of this new method lies in the fact that, as there is no sewing required, the sole leather does not need to be specially tanned and it is quite immaterial as to whether the said leather is firm or spongy, either type being equally suitable.

In the method of manufacture wherein the sole, welt and upper are sewn together, the sole becomes detached from the upper in a very short time owing to the stitches getting worn through by contact with the 100

ground. This disadvantage is entirely eliminated in the new method with the added advantage to the consumer in that the sole may be worn right through its entire thickness without becoming detached, owing to the fact that the nails or clips are inserted with their points in the direction of the under part of the sole. Furthermore, no nails or clips being on the inside of the shoe, these cannot by any means come in contact with the foot at any time.

This new type of shoe permits the use of any class of material, both for uppers or for soles; thus either tanned or raw hides, woven materials of any description, soles of different fibres such as plaited jute and the like may be used. This new method may be used in the manufacture of shoes of any type, price or quality.

20 It is evident that in the present new method for manufacturing shoes, certain details may be modified without this necessarily altering the principles of this invention, which are clearly set forth in the following claim.

25 Although I have shown the sole of my shoe to be made of a single thickness it is obvious that the sole may be made of a number of thickness secured together in any suitable manner.

30 Having now particularly described and ascertained the nature of my said invention and in what manner the same is to be performed, I declare that what I claim is:—

In a shoe, a sole, an upper, the edge of
35 said upper being out-turned adjacent the sole, a welt lying on said out-turned edge, said welt being split lengthwise to form a top flap, securing means passing through said welt, upper and sole, the upper surface
40 of said securing means being covered by said flap.

In testimony whereof I affix my signature.
LUIS HECTOR BARONE.
